UNITED STATES PATENT OFFICE.

JAMES MERRYWEATHER, OF GREENCASTLE, INDIANA, ASSIGNOR OF TWO-THIRDS TO ARTHUR THROOP AND HENRY H. HILLIS, OF SAME PLACE.

COUPLING FOR ELECTRIC CIRCUITS IN RAILWAY-TRAINS.

SPECIFICATION forming part of Letters Patent No. 593,965, dated November 16, 1897.

Application filed October 7, 1897. Serial No. 654,450. (No model.)

To all whom it may concern:

Be it known that I, JAMES MERRYWEATHER, a citizen of the United States, residing at Greencastle, in the county of Putnam and State of Indiana, have invented certain new and useful Improvements in Couplings for Electric Circuits in Railway-Trains, of which the following is a specification.

The object of my said invention is to provide an inexpensive, durable, and efficient means of coupling or connecting electric circuits, especially the signaling-circuits, in railway-trains at the same time the cars themselves are coupled, and which shall provide for all the variations incident to train movement—such as the swaying of the cars, &c.—and also which shall become automatically and easily disconnected when the cars separate, and thus sound the alarm or signal, but without damage to the appliances.

Said invention will be first fully described, and the novel features thereof then pointed out in the claims.

For purposes of simplicity of illustration and explanation I have shown my invention as applied to ordinary box freight-cars; but, obviously, it may be applied equally well to cars of any character or design. The circuits will be understood to be closed circuits, normally, in the use of which the alarm or signal is occasioned by opening or breaking the circuit. I have shown these coupling devices near the sides of the cars in the drawings in order that they should be shown as perfectly clear and distinct from the couplings and other construction. In practice, however, these electric coupling devices would be nearer the center of the cars—generally quite near to and, perhaps, in some cases partially or wholly underneath the draw-heads. Manifestly, however, such arrangement and location do not affect my invention, and such devices can be located at any convenient points.

Referring to the accompanying drawings, which are made a part hereof and on which similar letters of reference indicate similar parts, Figure 1 is a top or plan view of a portion of a railway-train provided with my improved electric-signal-circuit-coupling devices, one car being shown in full, with frag-

ments off the ends of two adjacent cars; Fig. 2, a side elevation of the same, the middle portion of the cars being broken away to save room; Fig. 3, a perspective view of the principal member of one of my improved coupling devices on a considerably-enlarged scale; and Fig. 4, a central sectional view thereof, showing also the other member near thereto and illustrating by means of dotted lines the positions which the parts assume in use and out of use.

In said drawings the portions marked A represent the body of the car, B the wires of the electric signaling-circuit, and C and D the two members of my improved coupler.

The cars, as heretofore indicated, may be of any usual or desired construction, and the wires are the usual wires of an electric signaling-circuit. Interposed at any point in such circuit in the cars or in the locomotive are such ordinary batteries, push-buttons or keys, and signal-bells or annunciators as the system selected and the needs of the particular service may require. None of these matters are peculiar to my present invention, and therefore will not be further described herein, except incidentally in describing the invention. Each car is provided upon each end with one member of my improved coupler, corresponding members always being located diagonally opposite to each other, so that any two cars similarly equipped and coming together will cause the coupling to take place. Each car thus, as will be observed, bears four of these coupling parts.

The wires B connect the coupling devices at the opposite ends of the cars upon which they are placed, each wire being connected at one end to a member C and at the other end to a member D, as shown.

The coupling parts C are box-like in form, and each has a pair of hinged or pivoted doors C' and C'', which, as best shown in Fig. 4, are normally held outwardly and toward each other by springs s, which are preferably wire springs coiled around the hinge-pivots of the doors, with one end of each of such springs bearing against the inner side of the corresponding door and the other end against the interior of the box-like structure. As will be readily seen, both these doors yield readily

when pushed against by a coupling part D, and the yielding may be variable, so that said coupling part D may be central, as shown in the drawings, or above or below the center 5 as the cars sway under the movement of the train. The edges of said doors are curved or rounded, so that the contact between them and the parts D will be continuously of uniform character.

10 The coupling parts D are plain stiff arms, and they are arranged to extend out, so as to pass into the box-like coupling part C between and in contact with the doors thereof.

Having thus fully described my said invention, what I claim as new, and desire to secure by Letters Patent, is—

1. The combination, with a railway-train having an electric signaling-circuit, of coupling devices consisting of male and female 20 coupling-halves adapted to be connected to the ends of the cars and to engage with each other, each car being equipped with two of each form of coupling-halves, one upon each end, the corresponding coupling-halves being 25 arranged in all cases diagonally opposite to each other, substantially as shown and described.

2. A coupling device for electric signaling-circuits on railway-trains, composed of the two halves C and D, each coupling-half C 30 being box-like in general form with swinging doors for the contact-surfaces, and the coupling-halves D each consisting of a plunger or arm adapted to pass into the box-like coupling-half C and in contact with the doors 35 thereof.

3. A coupler for electric signaling-circuits on railway-trains, consisting of a coupling-half C provided with two swinging doors C' C² having curved or rounded edges and provided with springs s for holding said doors toward their closed position, and a coupling-half D having an arm or plunger adapted to pass between and into contact with the doors of the first-described coupling-half, all substantially as shown and described. 40 45

In witness whereof I have hereunto set my hand and seal, at Indianapolis, Indiana, this 4th day of October, A. D. 1897.

JAS. MERRYWEATHER. [L. S.]
